(57) **CLAIM**

The ornamental design for an insole design, as shown and described.

DESCRIPTION

FIG. 1 is a bottom view of an insole showing the new design for use with the left foot;

FIG. 2 is a cross sectional view of FIG. 1 along line 2—2 thereof;

FIG. 3 is a right side view (as viewed from the top) thereof;

FIG. 4 is a cross sectional view of FIG. 1 along line 4—4 thereof;

FIG. 5 is a left side view thereof;

FIG. 6 is a prescriptive view from the right side thereof;

FIG. 7 is an end view thereof; and,

FIG. 8 is a bottom view of an insole for the right foot, the other views all being mirror images of those of the left foot. The portions in broken lines are for illustrative purposes only and form no part of the claimed design.

1 Claim, 3 Drawing Sheets

*FIG. 3**FIG. 2**FIG. 4*

FIG. 5

FIG. 8
